CONVERTIBLE EXCAVATOR

Joseph Albert Kuhsel, Altona, Germany

Application August 11, 1936, Serial No. 95,311
In Germany September 7, 1935

5 Claims. (Cl. 37—190)

My invention relates to power-operated excavators, and the particular object of the present invention is to so design a bucket-wheel excavator that it will excavate along any desired curve or slope.

In the appended drawing in which I have diagrammatically shown, by way of example, two embodiments of my invention, the two figures, Fig. 1 and Fig. 2, are side elevations. My invention, however, is not restricted to these, the main inventive idea residing in the replaceability of a bucket wheel as known in the art, with a shovel, grabbing crane or similar machine.

In the drawing, there is indicated at 1 the lower truck with its roller track, while 2 designates the revolving frame of a convertible shovel carrying power plant 3 and the hoist gear. For instance, as shown in Fig. 1 the boom 5 may be pivoted, instead of the standard shovel boom, to fulcrum 4, the end of the boom bearing bucket wheel 7 which is mounted to rotate round its shaft 6. The boom is held by rope 8 which passes over sheave 9 carried by frame 10 and sheave 11, carried by frame 12, to drum 13 of the hoist. When this drum is operated, the bucket wheel 7 can be lifted or lowered round fulcrum 4 of the boom. The bucket wheel is also rotated from the hoist. For instance, this could be done by the transmission of the rotation of a shaft provided in the machine, as for instance at 14, through bevel gears to shaft 15, and by another set of gears to bucket wheel 7. In order to be able to follow the distance variation between center line 6 of the bucket wheel and the center line of shaft 14, the shaft 15 rigidly held in its axial direction could be grooved longitudinally, as shown at 17 in Fig. 1, so that shaft 15 can slide through bevel gear 18 in accordance with eventual length variations. The same effect could, of course, be obtained by shaft 15 which transmits the torque being lengthened or shortened like a telescope. The bevel gear may be replaced with a chain drive, and the differences in length which occur when the bucket wheel is lifted and lowered, could be taken up by idlers. Besides, differences in length can be completely avoided by the driving torque from shaft 14 being transmitted for instance, by means of bevel gears or chains, to fulcrum 4 at the base of the boom, and from this point to the bucket wheel. The design of the bucket wheel in itself is well-known, and forms no part of this invention. The material dumped from the bucket wheel is transported, according to a well-known method, by means of a conveyor 25 which could for instance be arranged in such a way that it

empties the material into wagons 26. However, another conveyor which catches the material dumped by the first conveyor could also be provided, in order to transport this material rearwards or sideways.

Whenever, for instance with the embodiment shown in Fig. 1, soil is to be dug up to a certain height above ground, the curve *a*—*a* will be formed, as the bucket wheel can only move around fulcrum 4 of the boom. From this it can be seen that this attachment permits only of digging material up to a comparatively limited height, as otherwise the upper part of the bank would hang over and bring on a continuous risk of avalanching. Further, this attachment will not permit of excavating a slope under a predetermined angle without simultaneous propelling of the excavator truck in the direction of its boom. The arrangement shown in Fig. 2, however, will permit of digging, within wide limits, all desired curves and slope angles between the horizontal and the vertical, even without a change in the position of the excavator. This is obtained by the provision, at fulcrum 4 on frame 2, of a boom 19 the top of which is held by ropes 21. In this connection an existing boom, as for instance that of the shovel attachment, may be used. The boom extension or bucket wheel arm 22 is arranged between the fulcrum and the top of boom 19, at the point 20. The bucket wheel and its arm are held by rope 23 which passes over sheave 24 on boom 19 to drum 25^a of the hoist, and it can be lifted or lowered by means of the drum. Similarly, the boom 19 may be rocked in its vertical plane by operating drum 13 which accommodates rope 21 passing over sheave 11.

Now, by the operation of ropes 23, the bucket wheel 7 can be swung round fulcrum 20; in this way, the digging curve *b*—*b* will be obtained. As will be seen, the feature that fulcrum 20 can be raised to a higher level, will permit of digging into the bank up to a greater height without a deeper undercut. If drum 25^a is actuated at the same time as drum 13, and if the boom 19 is thus swung in its vertical plane, it is, for instance, possible to excavate a horizontal plane *c*—*c* by bringing the boom and wheel arm into the position as shown by dash-dotted lines, thus shifting fulcrum 6 of the bucket wheel from *d* to *e*. Similarly, by a displacement, for instance, from point *e*, and the simultaneous lifting of the boom and bucket wheel, a vertical wall can be dug as well as all intermediate slope angles. It will even be possible, by a suitable coordination of the two drums 13 and 25^a, as for instance by means of

a step gear, to dig any desired curve automatically, so that even without any particular attention from the operator, a straight bank or a level plane can be obtained. The same effect is accomplished by a selection of the number of the different ropes of pulleys 21 and 23 in such a way, or by arranging their points of attack of the boom or wheel arm at such a distance from fulcrums 4 and/or 20, that the bucket wheel automatically performs, upon the simultaneous operation of drums 13 and 25, a predetermined curve. Finally, the embodiment in Fig. 2 will permit of individual strata being extracted, as shown by the shading in Fig. 2. When the boom 19 is lowered further, this attachment will also permit of digging below ground level.

Likewise in this case, the bucket wheel 7 can be driven by bevel gears actuated by a shaft provided in the machine and from which the force is transmitted. The differences in length occurring between points 14 and 20 can be compensated for as has been above described; similarly, this design will permit of the above mentioned variations in the transmitting members. Also, the materials excavated by means of the bucket wheel can be transported by conveyors, for instance in the method described.

What I claim is:

1. In a power-operated apparatus, a revolving platform, a swinging boom provided thereon, a rotatable bucket wheel excavating tool carried by said boom, a hoisting means for said boom, a driving mechanism for operating the excavating tool, a shaft and cooperating gears providing a driving connection between said driving mechanism and said bucket wheel for rotating the latter, and means whereby the effective length of said shaft is varied responsive to swinging of the boom to maintain an operative connection between the driving mechanism and the bucket wheel for rotating the latter.

2. In a power-operated apparatus, a revolving

platform, a swinging boom provided thereon, a rotatable bucket wheel excavating tool carried by said boom, a hoisting means for said boom and a driving gear including a shaft and gear wheels for operating the excavating tool, the said shaft being longitudinally movable in one of said gear wheels.

3. In a power-operated apparatus, a revolving platform, a vertically swingable boom provided thereon, a hoisting mechanism for said boom, a second boom pivoted to said first-mentioned boom so as to swing in the same vertical plane therewith, a rotatable bucket wheel excavating tool carried by said second boom, and a driving means for rotating said bucket wheel.

4. In a power-operated apparatus, a revolving platform, a vertically swingable boom provided thereon, a hoisting mechanism for said boom, a second boom pivoted to said first-mentioned boom so as to swing therewith in the same vertical plane, a bucket wheel excavating tool carried by said second boom, a driving means for rotating said excavating tool, a conveyor in operative association with said bucket-wheel and a driving connection between said bucket wheel and said conveyor, said conveyor being pivoted to said second boom so that its rear discharge end is free to swing in a vertical plane.

5. In a power-operated apparatus, a revolving platform, a vertically swingable boom provided thereon, a hoisting mechanism for said boom, a second boom pivoted to said first-mentioned boom so as to swing in the same vertical plane therewith, a rotatable bucket wheel excavating tool carried by said second boom, a driving means for rotating said excavating tool, and means for separately hoisting said booms thereby permitting their swinging motions to be varied so as to enable any desired curve or slope to be excavated by said bucket-wheel.

JOSEPH ALBERT KUHSEL.
